UNITED STATES PATENT OFFICE.

CHARLES L. HARRISON, OF RICHMOND, VIRGINIA, ASSIGNOR OF ONE-THIRD TO
LEON L. STRAUSE, OF RICHMOND, VIRGINIA.

VENTILATOR SASH.

1,408,732.

Specification of Letters Patent.

Patented Mar. 7, 1922.

Application filed April 19, 1920. Serial No. 374,984.

To all whom it may concern:

Be it known that I, CHARLES L. HARRISON, a citizen of the United States, and residing at Richmond, in the county of Henrico and 5 State of Virginia, have invented a new and useful Ventilator Sash, of which the following is a specification.

The object of my invention is to provide an improved ventilator sash especially 10 adapted for use in car windows and adapted to permit of convenient regulation of the ventilation by the passenger and the convenient detachment and removal of the screen should it be necessary to replace 15 same; to provide an improved arrangement of the ventilator door with the knobs projecting but slightly beyond the surface of the sash, to provide an improved screen; and improved means for mounting and re- 20 moving same.

I attain the object of my invention by the mechanism illustrated in the accompanying drawings, in which—

Figure 1 is a front elevation of the invention applied to the window of a dining car;

Fig. 2 is a vertical section of the device;

Fig. 3 is a section on the line 3—3 of Fig. 2;

Fig. 4 is a rear elevation of the invention 30 viewed from outside the car;

Fig. 5 is a horizontal section on line 5—5 of Fig. 2; and

Fig. 6 is a detailed perspective view of one end of the screen and cinder guard.

Like numerals designate like parts in each 35 of the several views.

Referring to the accompanying drawings I provide a ventilator sash 1 having a cross rail 2 on the rear side of which is mounted 40 the ventilator door 3 horizontally secured to the cross rail 2 by hinges 16. Door 3 when closed abuts against the ornamental edge strips 23 of the ventilator opening. The bottom sash forms the inner ventilator 45 wall 4, the upper edge of which projects past the bottom edge of the outer detachable ventilator wall 7. Member 4 is provided with a suitable heavy rubber weather strip 5, as shown in Fig. 2. The top of the ven-

50 tilator is closed by the cover 8, shaped as shown in Fig. 2 and having its upper edge secured to the cross rail 2 by suitable screws 22 and having its lower inwardly bent portion 21 engaging the upper edge of the outer 55 ventilator wall 7. The outer ventilator wall

7 is detachably secured to side walls 6 by suitable screws 20, which permit of easy removal of wall 7. Wall 7 is provided with a suitable screen-supporting ledge 10. Screen 11 is removably mounted on ledges 10 60 and 9, it being possible to readily detach it when wall 7 has been detached. The side walls 6 are suitably secured to the sash as by screws 24. My improved form of screen consists of the screen 11 mounted in metal 65 side screen frames 13 and end screen frames 12. It is provided with a guard strip 14 extending at right angles to the main portion of the screen. I provide cinder guards 15 formed integrally with or rigidly secured to 70 the frame of the screen and positioned at either end, substantially as shown in Fig. 6. Guard strip or extension 14 is preferably formed integral with or is an extension of wall 7 and supports the screen frame 13, as 75 illustrated in Fig. 2, and frame 13 is provided with a depending securing flange or strip 26, as shown in Figs. 2 and 6. Secured to side walls 6 I provide flat end springs 18 adapted to frictionally engage the ends 19 of 80 ventilator door 3 to adjustably hold same in its adjusted position. I provide horizontal slots 25 in side walls 6 to receive the ends of screen 11.

As the ventilator door 3 is hinged to the 85 inner side of the cross rail 2 and is of less thickness than that member, the knob 17 is prevented from projecting to any more than a slight extent beyond the outer faces of members 2 and 4. The springs 18 frictionally engage the edges of the door 3 and hold it in position to which it has been adjusted. It will be observed that I have provided means for permitting of the convenient removal and replacement of screen 95 11 when desired. When desired to effect its removal screws 20 are withdrawn and outer ventilator wall 7 is removed, thus permitting the screen 11 with its attached cinder guards 15 to be withdrawn.

By the disposition of ventilator door 3 illustrated in the drawings, set in from the faces of members 2 and 4, I provide a construction that is mechanically more efficient because of the disposition of knob 17 and which also is much more ornamental in appearance.

The term "screen" is used by me as intended to designate any suitable screen member adapted to close the ventilator open- 110

ing, whether or not the particular preferred frame disclosed herein is used with the screen.

What I claim is:

5 1. In a device of the class described, the combination with a ventilator sash of a ventilator door vertically hinged to the inner side of the cross rail of the sash and adapted to close the ventilator opening, said 10 door opening inwardly and being disposed in a recessed position relative to the face of the sash, whereby the knobs carried by the ventilator door are prevented from projecting to an undesirable extent.

15 2. In combination with a ventilator having a swinging ventilator door, single flat springs mounted on the side walls of the ventilator adjacent the door and resiliently engaging the edges of the door whereby to 20 hold same in any desired adjusted position.

25 3. As a new article of manufacture for use in a ventilator of the type described, a combined screen and cinder guard comprising a screen, a frame in which said screen is mounted, cinder guard members formed integrally with the frame transversely at either end thereof and depending diagonally therefrom, and a guard strip extending longitudinally along one side of the frame 30 at right angles thereto.

35 4. In a ventilator sash the combination of a window having a ventilator combined therewith, the lower edge of the sash constituting the lower inner wall of the ventilator, a cross rail spaced above the bottom of the sash, a swinging ventilator door hingedly mounted to the inner side of the cross rail, the ventilator door being of less thickness than the cross rail, resilient means on 40 either side of the ventilator door frictionally engaging same to hold the door in adjusted position, a detachable ventilator cover, an outer detachable ventilator wall having its upper 45 portion of the cover, and having its lower edge projecting past the upper edge of the lower sash member which constitutes the inner wall of the ventilator, the lower portion of the aforesaid detachable wall projecting below the screen and functioning as a cinder guard, a screen supporting element mounted on the outer ventilator wall, the side walls of the ventilator being slotted, and a screen removably mounted in the slotted side walls, and a weather strip extending longitudinally of the screen member and adapted to be secured to the ventilator sash to firmly secure the screen in position attached to the sash, 95 substantially as shown.

cinder guard, a screen supporting element 50 mounted on the outer ventilator wall, the side walls of the ventilator being slotted, and a screen removably mounted in the slotted side walls.

5. A ventilator sash having the ventilator 55 mounted on and forming the bottom portion of the sash, and comprising side walls secured to the sash, a cover for the ventilator, spaced ventilating walls having their free edges projecting past the same horizontal 60 plane, the side walls having horizontal slots therein, a screen removably mounted in the slots in the walls of the ventilator, a swinging ventilator door and resilient means for holding said ventilator door in adjusted 65 position.

6. In a ventilator sash, the combination of a window having a ventilator combined therewith, the lower edge of the sash constituting the lower inner wall of the ventilator, side walls secured to the sash, a cross rail spaced above the bottom of the sash, a swinging ventilator door hingedly mounted to the inner side of the cross rail, the ventilator door being of less thickness than the cross rail, resilient means on either side of the ventilator door frictionally engaging same to hold the door in adjusted position, a detachable ventilator cover, an outer detachable ventilator wall having its upper 80 edge in contact with the lower portion of the cover, and having its lower edge projecting past the upper edge of the lower sash member which constitutes the inner wall of the ventilator, the lower portion of the aforesaid detachable wall projecting below the screen and functioning as a cinder guard, a screen supporting element mounted on the outer ventilator wall, the side walls of the ventilator being slotted, and a screen removably mounted in the slotted side walls, and a weather strip extending longitudinally of the screen member and adapted to be secured to the ventilator sash to firmly secure the screen in position attached to the sash, 85 90 substantially as shown.

CHARLES L. HARRISON.
